UNITED STATES PATENT OFFICE.

JACOB W. MILLER, OF HANOVER, PENNSYLVANIA.

RADIATOR-CORE.

1,394,857.

Specification of Letters Patent.

Patented Oct. 25, 1921.

Application filed August 13, 1920. Serial No. 403,244.

To all whom it may concern:

Be it known that I, JACOB W. MILLER, a citizen of the United States, residing at Hanover, in the county of York and State 5 of Pennsylvania, have invented certain new and useful Improvements in Radiator-Cores, of which the following is a specification.

The invention relates to improvements in 10 radiator cores.

The object of the present invention is to improve the construction of radiator cores and to provide a simple, practical and efficient radiator core of strong, durable 15 and comparatively inexpensive construction equipped with horizontal triangular seamless cells forming separate tubes and spaced apart between their terminals to form intervening water circulation spaces and provided 20 with interiorly arranged means for separating the air and causing the same to impinge alternately against the cells at opposite sides of the splitting device whereby an efficient cooling system is provided in connection 25 with the water circulating system afforded by the spaced triangular cells.

Another object of the invention is to provide a radiator core from which one or more of the radiator cells may be readily removed 30 for repair or replacement without injury to the rest of the cells of the core.

It is also an object of the invention to enable the air splitting devices to be readily removed from the triangular cells and in 35 which the triangular cells will operate to maintain the air splitting devices firmly in a central position within them.

With these and other objects in view the invention consists in the novel construction, 40 combination and arrangement of parts hereinafter fully described, illustrated in the accompanying drawings and pointed out in the claims hereto appended, it being understood that various changes in the form, proportion 45 and minor details of construction, within the scope of the claims, may be resorted to without departing from the spirit or sacrificing any of the advantages of the invention.

50 In the drawing in which like characters of reference designate corresponding parts in the several figures:

Figure 1 is a front elevation of a radiator provided with a core constructed in accordance with this invention.

Fig. 2 is a plan view of the core removed from the frame of the radiator.

Fig. 3 is a vertical sectional view taken transversely of the cells.

Fig. 4 is a detail perspective view of one of the cells.

Fig. 5 is a similar view of one of the air splitting devices.

In the accompanying drawing in which is illustrated the preferred embodiment of the invention the radiator core which is arranged within a radiator frame 1 is designed for use on various types of automobiles, motor vehicles and the like, and the radiator frame 1 may be of any desired construction 70 and is equipped with the usual inlet and outlet tubes 3 and 4. The radiator core is composed of triangular cells 5 constructed of copper or other suitable metal and provided with bell or flared ends 6 which when the 75 cells are assembled in the core fit against one another and space the body portions of the cells from each other to provide intervening water circulation spaces. The triangular cells are arranged to form inclined 80 and vertical intervening water spaces and the contiguous ends of the cells are secured together by soldering or other means, the soldering permitting one or more cells to be readily removed from the radiator core by 85 the use of a blow pipe. Also in the event of a leak caused by injury or wear of a tube the leak owing to the horizontal arrangement of the cells will be localized and the form or injured cell may be readily removed 90 without removing or injuring the adjacent cells.

The cells form separate arms and extend through the radiator frame from front to rear and they are equipped with air separating devices or members 7 consisting of strips of copper or other suitable metal arranged centrally of the cells and fitting in and extending from one angle to the center of the opposite side and provided thereat with a flange 8, fitted against the said side and preferably secured to the same by solder or other suitable means. The fitting of the air splitting strip or member in the angle of the triangular cell obviates the necessity of soldering the strip or member thereat and the said angle will firmly maintain the contiguous edge of the air splitting strip or member in a central position and prevent lateral movement of the same. Each air split- 110

- ing strip or member is provided with integral air deflecting tongues or portions 9 preferably of triangular shape formed by cutting the metal of the strip or member 5 and bent laterally alternately on opposite sides of the said strip or member and extending toward the front of the radiator whereby the air is alternately directed through the openings 10 to opposite sides of 10 the air splitting member and is caused to impinge alternately against opposite sides of the interior of the triangular cell thereby forming an efficient cooling system for reducing the temperature of the water passing 15 through the radiator. The openings 10 are formed by the cutting of the tongues and the flanges 8 may extend to either or both sides of the cells. The core may be of any desired size and may contain any number of 20 cells which may be of any desired length and any suitable number of air deflecting tongues or portions may be provided. The bell or flared ends besides separating the body portions of the cells form enlarged air- 25 receiving terminals for collecting and forcing the air through the cells of the core. The triangular cells are arranged with their sides vertical and inclined as shown so as to produce a free positive gravity feed of the 30 water from the top to the bottom of the core and laterally of the latter for spreading the water and thoroughly subjecting the same to the cooling action of the core.
- If the use of the machine in which the 35 radiator is employed will not permit of interruption long enough to make repair, the radiator may be used continuously without interruption by simply plugging the leaky cell at opposite ends. The radiator core 40 presents an ornamental appearance when viewed from either front or rear.
- What is claimed is:
1. A radiator core including horizontal triangular cells connected at their ends and 45 having their body portions spaced apart to form intervening circulating spaces, said triangular cells each having one of their sides arranged vertically and their other sides at an inclination to form only vertical 50 and inclined intervening water circulating spaces to produce a positive gravity flow of the water from the top to the bottom of the radiator throughout the entire water spaces.
  - 55 2. A radiator core including horizontal triangular cells connected at their ends and having their body portions spaced apart to form intervening water circulating spaces and air splitting devices arranged centrally 60 of the cells and extending longitudinally thereof, each air splitting device having one of its longitudinal edges fitted in the angle
- of its cell and thereby maintained centrally of the same, said air splitting devices being provided with openings and having means 65 therat for deflecting the air through the openings to cause the same to impinge alternately against the opposite sides of the cells.
3. A radiator core including horizontal triangular cells connected at their ends and 70 having their body portions spaced apart to form intervening water circulating spaces and centrally arranged air splitting strips or members extending longitudinally of the cells and each fitted at one edge in one of the angles of a cell and provided at the opposite side of the cell with a flange fitted against the said side, said air splitting strips or members being provided at intervals with 75 openings and having deflecting means arranged at the openings for causing the air to impinge alternately at opposite sides of the cells.
4. A radiator core including horizontal triangular cells connected at their ends and 80 having their body portions spaced apart to form intervening water circulating spaces and centrally arranged air splitting strips or members extending longitudinally of the cells and each having one of its longitudinal 85 edges fitted in one of the angles of a cell and extending to the center of the opposite side of the cell and provided therat with a laterally extending projecting flange extending to the side of the cell and adapted to be 90 attached to the latter, said air splitting members or strips being provided at intervals with openings and having air deflecting tongues therat.
5. A radiator core comprising horizontal 95 triangular cells provided with flared or bell ends fitted together and spacing the body portions of the cells to form intervening water circulating spaces said cells having their sides arranged vertically and at an inclina- 100 tion to produce a positive downward and lateral flow of the water by gravity from the top to the bottom of the radiator core, and central longitudinal air splitting strips or members arranged within the cells and 105 fitted at one of the longitudinal edges in an angle of the cells and extending to the center of the opposite side of the cell and provided therat with a longitudinal flange extending laterally to one side of the cell said 110 strips or members being provided at intervals with openings and having integral air deflecting tongues located at the openings and extending upwardly at opposite sides of the strips or members to cause the air to 115 impinge alternately against opposite sides of the cells.
- In testimony whereof I affix my signature.
JACOB W. MILLER.
